UNITED STATES PATENT OFFICE

AURELIO RODRIGO EGUREN, OF PARIS, FRANCE

SAFETY BUTTON

Application filed March 27, 1930, Serial No. 439,484, and in France March 30, 1929.

The present invention relates to a safety button adapted for the closing of the inside pockets of garments, in order to prevent the loss of objects placed in such pockets; such as pocket books, or to prevent the theft of such objects.

All drawbacks inherent in the known devices are obviated by the button device according to the invention, which affords great safety and is also of a simple construction.

In principle, the button device is disposed on closing in the same manner as an ordinary button disposed adjacent a button-hole formed on the pocket, and it can optionally be provided with a fastening device combined therewith, and thus pocket will be kept closed when required.

The chief characteristic of the invention consists in the fact that the base plate and the head of the button are joined by two parallel rods or shanks, so disposed as to allow between them a space sufficient for the engagement of the fastening device with which the sail button is combined, so as to hold the head of the button in the button-hole after this head has been inserted through it.

The button is attached by sewing it through perforations in the base plate, which form a circular row, while at the same time disposing the two rods in the vertical plane in line with the button-hole.

The device for fastening the head of the button to prevent it from accidentally leaving its buttonhole, consists essentially of a fastener having the form of a split ring or the curved shackle of a padlock, which may be engaged between the two rods or shanks. However, the said fastening device may also consist of a sort of clasp whose branches make contact with the said shanks. This latter device may comprise a hinged lug which is sewed at a point below the button-hole.

By way of example, the said invention will be described with reference to the accompanying drawings, in which:

Fig. 1 is a side elevational view of the button.

Fig. 2 is the corresponding plan view.

Fig. 3 is a front view of the button when applied, the pocket of the garment being open.

Fig. 4 is a front view of the fastening device consisting of a split ring.

Fig. 5 is a front view of said ring when applied to the button.

Fig. 6 is a corresponding side view.

Fig. 7 is a front view of the fastening device, which consists of a clasp.

Fig. 8 is a front view of the same when applied.

Fig. 9 is a corresponding side view.

Fig. 10 is a front view of the fastening device, which consists of a small padlock.

Fig. 11 is a front view of a modification.

As shown in Figures 1 and 2, the button itself has preferably a round form and is made in one piece with its base plate a , its rods or shanks a^1 and its head a^2 . The head is round, and its periphery is convex at its surface, while the base has a larger diameter than the head and is flat, being pierced with a concentric row of perforations a^3 ; and it has a flat part with which its position is determined with reference to the pocket.

The said button is sewed to the cloth of the garment b (Fig. 3) and herein the thread is inserted through the perforations a^3 ; the whole is readily attached, due to the said flat part, in such manner that the two shanks a^1 of the button are exactly in the vertical plane with the head opposite the buttonhole c which is also vertical.

The two shanks a^1 connecting the base to the head of the button are somewhat spaced apart, and thus the general shape of this connecting part consisting of the two shanks will be flat, thus properly coinciding with the opening of the buttonhole c .

Said button is sewed directly to the inner side of the garment; when the pocket d (Fig. 3) has no covering flap, and herein the buttonhole c is situated on the pocket. In the case of a pocket provided with such a cover flap, the button is sewed to the pocket, and the buttonhole is formed in the sail flap. In the present example, the button is sewed directly to the garment.

The said button may be used as it is, like an ordinary button.

When the fastening device which is combined with this button, and which may be 5 optionally employed, consists of a removable split ring e (Figs. 4, 5 and 6), the ring is provided on the side opposite the opening e^1 with a part e^2 having the shape of a fork, and on the other side is a right angle end.

10 To place the ring upon the button which has been inserted into its buttonhole, the opening e^1 of said ring is placed upon the upper shank of the button, and then the branches of said ring are drawn apart so 15 that they will clear this first shank and will again come together between the two shanks; the ring is then given half a turn in order that the fork e^2 of said ring may engage upon the lower shank of the button, 20 (Figs. 5 and 6), thereby fastening the said button.

The inverse operation permits, by bringing the said ring into such position that its opening e^1 will coincide with the lower 25 shank a^1 of the button, to release the button from its fastening device by drawing down the said ring e , which is held by its end part e^2 .

The fastening device combined with the 30 said button may also consist of a sort of clasp with two elastic branches, so disposed as to pivot in a securing hinge (Figs. 7, 8 and 9).

The said device may consist of iron wire f 35 and at the two ends of the wire is formed a large opening f^1 having the form of a stirrup and adapted to receive the hinge f^2 , and to allow the free insertion of the head a^2 of the button; the branches then come together in order to form clamps at f^3 , thus laterally surrounding the two shanks a^1 of the button. Said branches are brought together so as to meet at a point near their 40 part f^4 , thus forming at this point an arrangement for operating the device.

The securing hinge f^2 is perforated in order that it may be sewed to the pocket below the buttonhole c , at such a distance from the button that the latter may be 45 fastened without folding the cloth.

The hinge f^2 and the said fastening device pivoted thereto are disposed on the garment in the following manner:

The button is engaged in the buttonhole 50 55 in order to close the pocket, and the head of the button is then inserted into the large opening f^1 of the fastening device.

This device is lowered until the two shanks a^1 of the button are engaged in the part f^3 60 of the fastening device (Figs. 8 and 9).

The hinge is then sewed to the pocket, and the button is fastened.

To release the button, the button and the hinge are brought together by folding the 65 cloth, and this brings the head of the button

into the part f^1 of the fastening device which has the largest opening, then turning down this device by pivoting it in its hinge f^2 to unbutton the parts.

The parts can be again fastened by raising the fastening device, then bringing the button near the hinge, so as to engage the button in the part f^1 of the device, which is then lowered into the position shown in Figs. 8 and 9.

70 It is also feasible to use with this button, as a fastening device, a small padlock g known per se (Fig. 10), its curved holder g^1 being engaged between two rods a^1 of the button, then securing the said curved holder 75 by a key.

The said padlock may be replaced by any suitable device.

In the construction shown in Fig. 11, the fastening device is so constructed as to be employed with buttons of the kind represented in the drawings, as well as with an ordinary button without base plate which is sewed to the garment.

80 The device shown in this figure is constructed in the form of an elastic clasp consisting of a steel wire, suitably bent into shape so as to offer two curved branches f having between them a space f^1 and joined by a loop f^2 in which is engaged the shank a^1 , or the sewing thread of the button to be fastened. The two branches f each have an eye f^3 in which is freely slideable a horizontal extension f^4 of each branch, ending in a right angled part f^5 .

85 Obviously, all suitable modifications may be made in the forms, details, accessories, material and dimensions of the said button, and thus, for instance, the button itself might comprise a wide and flat rod apertured for the insertion of the split ring of the curved shackle of the padlock. A wide and flat rod without perforation may be used when the button is combined with a holding device in the shape of a clasp.

90 Furthermore, the said safety button can be employed, according to the invention, with all objects adapted for its application.

95 Having described my invention what I claim as new and what I desire to secure by Letters Patent is:

100 1. A button of the character described comprising a base plate having means formed thereon for securing to an article to be buttoned, a button head adapted for insertion through the buttonhole, spaced parallel shanks having their ends fixed to one face of said base plate and button head, and means insertable between said shanks to maintain the button in its buttoning position.

105 2. A button of the character described comprising a base plate having means formed thereon for securing to an article to be buttoned, a button head adapted for 110

insertion through the buttonhole, spaced parallel shanks having their ends fixed to one face of said base plate and button head, and a split ring adapted to be inserted between said shanks and engage therebetween to maintain the button in its buttoning position.

3. A button of the character described comprising a base plate having means formed thereon for securing to an article to be buttoned, a button head adapted for insertion through the buttonhole, spaced parallel shanks having their ends fixed to one face of said base plate and button head, and a split ring adapted to be inserted between said shank and engaged in the space between the same, said ring having at a point diametrically opposite the split portion thereon, a fork bracket engageable with one of said shanks whereby to maintain the button in its buttoning position.

4. A button of the character described comprising a base plate having means formed thereon for securing to an article to be buttoned, a button head adapted for insertion through the buttonhole, spaced parallel shanks having their ends fixed to one face of said base plate and button head, and a fastening device consisting of a small padlock insertable and engageable between said shanks for maintaining the button in its buttoning position.

In witness whereof I have hereunto set my hand.

AURELIO RODRIGO EGUREN.
